CLAIM

I claim the ornamental design for shotgun wad, as shown and described.

DESCRIPTION

FIG. 1 is a perspective view of a shotgun wad according to the invention. The wad is rotationally symmetric about a longitudinal axis wherein the view from the opposite side being identical thereto; and,

FIG. 2 is a perspective view of a shotgun wad according to the invention. The wad is rotationally symmetric about a longitudinal axis wherein the view from the opposite side being identical thereto.

The portions shown in broken lines form no part of the claimed invention. The interior of the wad does not form part of the claimed design.
